UNITED STATES PATENT OFFICE.

FRANK S. WARREN, OF CONCORD, NEW HAMPSHIRE.

PIANO ATTACHMENT.

SPECIFICATION forming part of Letters Patent No. 443,156, dated December 23, 1890.

Application filed September 16, 1890. Serial No. 365,127. (No model.)

To all whom it may concern:

Be it known that I, FRANK S. WARREN, a citizen of the United States, residing at Concord, in the county of Merrimac and State of New Hampshire, have invented certain new and useful Improvements in Piano Attachments, of which the following is a specification.

This invention relates to "tone-mufflers" for pianos, the object of the invention being to provide mechanism whereby the sound may be deadened without interference with either the soft or loud pedal, both of which may be used with good effect in connection with a tone-muffler by aid of my improvements.

The invention will be fully set forth in the following specification and claims, and clearly illustrated in the accompanying drawings, forming a part thereof, of which—

20 Figure 1 represents a cross-section of the bar, carrying an apron of felt or similar material forming the muffler, and one of the end supports or brackets with its operating-cam in elevation. Fig. 2 is a view of the same 25 parts shown in the previous figure in another position. Fig. 3 represents a front elevation of the mechanism shown in previous figures.

Similar reference-letters indicate corresponding parts.

30 An ordinary muffler-apron A is attached to the bar B, and the latter is mounted at either end upon a swiveled bracket C, which may be pivoted by means of a screw D to the end frame Y of a piano.

35 My improved mechanism for rocking the bar B, carrying the apron A, is applied to but one of the brackets C, and is intended to be operated by a pedal in either direction and independent of the soft and loud pedals of a 40 piano, in the following manner:

Upon the lower part of the bracket C are provided projections c c, extending from its face, one at either side of its fulcrum-screw D. Between these projections c c is placed 45 an operating-cam E, having shoulders e e, located at opposite sides for engaging the lower edge of either projection c of the bracket at each upward stroke of said cam, and upward and outward inclined portions e', for 50 engaging the upper curved side of either pro-

jection c of the said bracket at each down-stroke of said cam. The lower end of said cam E is pivoted at f to the upper end of a vertical rod F, moving in a socket provided for this purpose in the end frame Y, which 55 may be raised by a suitable pedal attachment and dropped by gravity. Thus the said cam may rock forward or backward sufficiently to conform to its requirements to engage first one and then the other of the projections c of the bracket C.

The line X represents a string in its position relative to my improved attachment. In Fig. 1 the bar B and bracket C are shown in position to hold the muffler A away from the 65 strings; but by raising the rod F and cam E that shoulder e which is directly under the lowest projection c of the bracket C will by contact with the same throw the said bracket to the position seen in Fig. 2, which places the said 70 muffler A in contact with the strings X, and lowers it sufficiently to receive the blow of the hammers while the keys of the instrument are in use, and in falling back to its normal position that inclined portion e' which 75 is upon the same side as the shoulder e, used in throwing the muffler into contact with the strings by sliding down upon the projection c upon the same side of the bracket C, is thrown over ready to form contact with the 80 other projection c, and by another upward motion to again place the muffler in the position seen in Fig. 1, and so on. At each upward movement of the rod F the muffler is alternately moved on or off the strings. 85

In order that the cam may not become displaced, a suitable cap-piece G is placed over the cam and lower part of the bracket, as seen in dotted lines, Figs. 1 and 2, and full lines in Fig. 3, provided with perforated bearings at each corner, through which fastening-screws H may be passed into the end frame Y, the upper bearings g serving as stops for limiting the movement of the bracket. 90

Having described my invention, what I 95 claim as new is—

1. In a tone-muffler, the combination of a swiveled bracket provided with projections c c and a suitable cam provided with shoulders for engaging the under side of said projec- 100

tions and inclined surfaces for engaging the upper or curved side of said projections, all substantially for the purpose set forth.

2. In a tone-muffler, swiveled brackets supporting the rod carrying the muffler, one of said brackets being provided with projections, as shown, and a reciprocating cam having shoulders and inclined portions for engaging said projections on the bracket, where-

by the muffler may be applied by a single movement of said cam, and vice versa.

In testimony whereof I affix my signature in presence of two witnesses.

FRANK S. WARREN.
